UNITED STATES PATENT OFFICE.

JAN PROCNER, OF PABIANICE, NEAR LODZ, RUSSIA.

REVERSIBLE STEAM-TURBINE.

No. 892,304.

Specification of Letters Patent.

Patented June 30, 1908.

Application filed April 11, 1908. Serial No. 426,551.

To all whom it may concern:

Be it known that I, JAN PROCNER, a subject of the Czar of Russia, residing in Pabianice, near Lodz, Kingdom of Poland, and 5 Empire of Russia, have invented certain new and useful Improvements in Reversible Steam-Turbines, of which the following is a specification.

Owing to the well known difficulty of reversing steam- and gas-turbines, for such 10 power applications as require a quick and easy reversibility (for instance, for seagoing vessels or vehicles, lifting machines, load-raising machines, etc.), the use of turbines is 15 connected with serious objections. In most of these cases, as, for instance, in applying steam-turbines to vessels, it is necessary to provide special steam-turbines for backward motion. The various attempts which have 20 been made to construct a steam-turbine reversible in itself have so far not produced a simple and safely working turbine as a solution of this problem.

The object of this invention is to furnish 25 an improved steam-turbine in which the action of the steam against the vanes or buckets is controlled, and which is reversible in a simple and reliable manner.

The essential improvements of the new 30 construction consist in that, instead of having the steam-nozzles stationary and the bucket-wheel rotatable, as is usually the case, two or more steam-nozzles are mounted upon hollow arms mounted radially on the 35 turbine-shaft. Said nozzles are capable of oscillation about the longitudinal axis of said arms so as to coöperate with one or the other of two series of bucket-rings arranged on the inner surfaces of opposite side-walls of each 40 pressure-chamber. Said hollow arms are mounted on the shaft in such a manner that by manipulating the shaft in a certain way the arms may be oscillated so as to bring the nozzles into coöperation with either system 45 of bucket-rings. The bucket-rings of the two systems are oppositely arranged so that the arms will rotate in one or the other direction according as the nozzles are brought into coöperative relation with one or the other 50 system of bucket-rings, so that the reversal of the turbine is obtained by oscillating the nozzle-carrying arms. Located within the hollow arms are mechanisms for adjusting

the nozzles, and these mechanisms are also operated from the turbine-shaft.

The effective working of a steam-turbine constructed according to this invention can be considerably increased by having short segments of buckets, which are shaped so as to correspond with the bucket-rings on the 60 side-walls of the pressure-chambers, oscillate simultaneously with the steam-nozzles about the supporting arms for the latter so that said segments may be brought into coöperative relation with one or the other of the 65 oppositely arranged bucket-systems, whereby the reaction effect in both directions is augmented.

In the accompanying drawing, Figure 1 is a side-elevation of a horizontal three-stage 70 steam-turbine constructed in accordance with the invention, Fig. 2 is a vertical longitudinal section of Fig. 1 drawn on a larger scale, with parts at the end of the turbine omitted, Fig. 3 is an end-view of the turbine 75 looking from the left of Fig. 1 and showing the controlling slide and its adjacent parts, Fig. 4 is a vertical transverse section, showing the interior of one of the pressure-chambers and the nozzle-carrying arms arranged there- 80 in, Fig. 5 is a similar section taken through the hollow nozzle-carrying arms, Figs. 6 and 7 are detail views showing the form and arrangement of the controlling slide, and Figs. 8 and 9 are detail views of the adjusting 85 mechanism for the nozzles.

Similar characters of reference indicate corresponding parts throughout the several views.

Referring to the drawing, A denotes the 90 casing of the turbine which is of the horizontal three-stage type, having three pressure-chambers 14, 15, 16. The improved turbine has a compound shaft which is made partly solid, partly tubular, and partly provided with channels, and which in the construction shown in the drawing is formed of four parts or sections a, b, c and d (Fig. 2). The turbine-shaft turns in two journal-bearings e and f and supports on hollow hubs 100 three pairs of radial, rotatably mounted, hollow nozzle-supporting arms g, h, i. Side-wise of the nozzle-supporting arms are arranged the nozzle-housings j, k, l, shown in Figs. 2 and 5, which are provided with adjustable nozzle-openings of rectangular cross-

section. The nozzle-carrying arms *g*, *h*, *i* are provided at their inner ends with bevel gear-wheels *m*, *n*, *o* which mesh with bevel gear-wheels *m*₁, *n*₁, *o*₁ which are concentrically rotatable in the hubs.

- In the shaft *a*, *b*, *c*, *d* are arranged two concentric spindles, a hollow one *p* and a solid one *q*, as best shown in Fig. 8. The spindle *p* is provided with collars *r*, *s*, *t* which are 10 provided on their circumference with screw-threads of high pitch and which are fitted into the bored out hubs of the bevel wheels *m*, *n*, *o* which are provided with corresponding threads. To the spindle *q* are fastened 15 split rings *u*, *v*, *w* by means of keys that are passed through the same. These rings are also provided on their circumference with screw-threads of high pitch and fitted into the bores of the hubs of the slide-pieces *x*, *y*, 20 *z*, shown in Fig. 8, in which the corresponding female thread is located. The slide-pieces are rotatable at the interior of the engine-shaft, but not longitudinally shiftable along the same.
- 25 In the hollow nozzle-supporting arms *g*, *h*, *i* are located rods 1, 2, 3 which are shiftable along the arms and which are provided at their inner ends with forks, the bolts of which are arranged shiftably in the eccentric guides 30 of the slide-pieces *x*, *y*, *z* (Fig. 8). In the outer ends of the rods 1, 2, 3 are located rotatable heels 4, 5, 6 which operate the shifting rods 7, 8, 9 of the nozzles in centrifugal or centripetal direction, whereby larger or 35 smaller cross-sections of the nozzle-openings are obtained.
- The spindle *p* is prevented from rotating by the keys 10. It can only be shifted in axial direction by means of the steam-piston 40 ton 11 which is located in the steam-cylinder 12. The spindle *q* can likewise be shifted only in axial direction by means of the hand-wheel 13 and the screw-thread on the hub of the same. The spindle *p* serves for reversing 45 the turbine and the spindle *q* for enlarging or diminishing the outlet cross areas of the nozzles. Both spindles are rotated with the engine-shaft *a*, *b*, *c*, *d*, and these with the nozzle-supporting arms are rotatable in the 50 stationary turbine-chambers 14, 15, 16. On the flat inner surfaces of the side-walls of the turbine-chambers are arranged two guide-bucket systems 17, 18, 19 for turning towards the right and two guide-bucket systems 55 20, 21, 22 on the opposite side-walls for turning towards the left. On each nozzle-carrying arm are located under the nozzle two bucket-segments 23, 24, 25, as shown in Figs. 2 and 4. These segments consist of a few buckets which take up the steam-jet that is delivered by the nozzle and conduct the same, and which by an oscillation of the nozzle-carrying arm for 180° are moved from the position between the guide-bucket systems 17, 18 and 19 without outlet

into the proper place between the guide-bucket systems 20, 21, 22. During each reversal the steam supply to the turbine is automatically interrupted. This interruption is obtained by means of a piston 26 which is moved in the cylinder 28 by the steam and has a slide 27 to close the steam-inlet 30.

At both ends of the two controlling cylinders 12 and 28 are arranged double pipe connections *d*₄ *v*₂, *d*₂ *v*₄ *d*₃ *v*₁, *d*₁ *v*₃. They are connected by means of thin pipes with similarly designated ports on the controlling slide (Fig. 6). The controlling slide is located sidewise of the turbine in convenient proximity thereto and is operated by means of a hand-wheel 29 and the screw-spindle of the same. The port *d*₅ on the controlling slide is connected with the steam-supply pipe by means of a pipe and likewise in the same manner by a port *v*₅ with the vacuum-chamber of the turbine.

The operation of the turbine is as follows: The steam enters through the opening 30 a radial channel 31 and a few axial channels 32 into the first hollow section *a* of the engine-shaft; from the same it passes to the two nozzle-carrying arms *g* into the nozzle-housing *j* and through the lower, laterally arranged nozzle-exits, shown in Figs. 2 and 5, into the turbine-chamber 14 in which a lower pressure is present than in the nozzle-carrying arms *g*, so that by the reaction of the steam-jet on the wall opposite to the nozzle-openings, the nozzle-carrying arms are rotated in a direction opposite to the direction of the steam-jet. The steam is emitted from the nozzle with a velocity which is dependent on the pressure phase of the same. This velocity is utilized in such a manner that the steam-jets are taken up by stationary guide-buckets and repeatedly conducted to the buckets that are fastened on the nozzle-carrying arms, once or twice in succession, until the velocity of the same in the first pressure stage is utilized, so that the steam is expanded between the buckets. The steam then passes between the angular-shaped channels 33 and is conducted into the cavity in the shaft-section *b*, from the same into the nozzle-arms *h*, nozzle-housing *k*, and from the nozzle-shaped openings in the same to the second turbine-chamber 15 in which the pressure is lower than in the nozzle-carrying arms *h*. By the reaction during the outlet of the steam the nozzle-arms *h* are rotated in the same direction as the arms *g*, whereby the steam-jets are conducted through the guide and main buckets in the same manner as in the first turbine-chamber in radial centrifugal direction so as to accomplish work until the velocity of the same is fully utilized and the steam expanded to the next lower pressure. From the second turbine-chamber the steam is conducted through the angular channels 34 to the opening of the shaft-section *c* and from

the same to the arms *i*, the nozzle-housings 1 and the nozzle-shaped outlets of the same to the third turbine-chamber 16, which is at lowest pressure. In the chamber 16 the velocity of the steam-jets is utilized in the same manner as in the two preceding chambers, after which the fully expanded steam is conducted through the openings 35 into the condenser. In consequence of the diminishing 10 or enlargement of the cross-sectional areas of the nozzle-openings in all nozzles simultaneously by means of the mechanism arranged for this purpose which is operated by the hand-wheel 13, smaller or larger quantities of 15 steam are emitted under the same pressure proportions between the individual pressure stages so that smaller or larger rotary velocities of the turbines are obtained and the effective force of the turbine is correspondingly changed.

The reversal of the turbine is effected by actuating the steam-piston 11 within the cylinder 12 in such a manner that the spindle *p* is shifted longitudinally. In this manner 25 through their connections with said spindle the hollow nozzle-supporting arms are turned on their axes through 180° , carrying with them their steam-nozzles and bucket-segments, so that said nozzles and segments are 30 brought into coöperation with the bucket system arranged on the opposite side-wall of each pressure-chamber. When the nozzles are to be adjusted the spindle *q* is actuated by the hand-wheel 13 as before described, whereupon, through their connections through said 35 spindle, the nozzle-adjusting rods 1, 2, 3 will be actuated in such a manner as to increase or decrease the effective cross area of the nozzles. Thus the reversal of the turbine and 40 the adjustment of the steam-nozzles are both effected by the longitudinal movement of spindles arranged within the hollow turbine-shaft. The automatic interruption of the steam during the reversal is effected through 45 the connections between the steam-cylinder 28 with the controlling slide, as has already been explained. When the piston 11 in the cylinder 12 is operated upon by the steam so as to shift the spindle *p* and reverse the turbine, connection with the cylinder 28, is made 50 in such a manner through the controlling slide that the slide 27 on the piston 26 moves across and closes the inlet 30 for the live steam.

The steam pressure and the vacuum are sustained against the atmosphere between the turbine-chambers by the doubly divided labyrinth packings 36, 37, 38, 39, 40. The proper distance between the ring surfaces of 55 the engine-shaft and the ring surfaces of the doubly divided packings is regulated and fixed by corresponding forked levers 41, 42, 43, 44, 45 and by bolts 46, 47, 48, 49, 50, as shown in the drawing. The levers and bolts 60 take up also the side pressure of the steam on

the face surfaces of the packings. The proper distance of the turbine-chambers from each other is retained by the intermediate pipes 51, 52. The free expansive capacity of the turbine-shaft by the heat is obtained in 70 such a manner that the shaft is only secured against side-shifting in the journal-bearings *f*; but it is movable in axial direction in the journal-bearings *e*. 53 represents one member of the coupling by which the power is 75 transmitted to the shaft connected with the outer end of the turbine-shaft. In turbines with a simple constant number of rotations the reversing mechanism is dispensed with, likewise the guide-bucket system is in the 80 turbine-chambers on one side and the automatic steam throttling. The spindle *q* for the adjustment of the cross-sections of the nozzle-openings is in this case, in place of the hand-wheel 13, subjected to the action of a 85 regulator which shifts it to and fro.

Having thus described my invention, I claim as new and desire to secure by Letters Patent:

1. In a steam-turbine, the combination of 90 a pressure-chamber, bucket systems arranged on opposite side-walls thereof, a shaft rotatable in said chamber, a nozzle-carrying arm mounted on said shaft within said chamber, and means for turning said arm to bring it 95 into coöperative relation with either bucket system.
2. In a steam-turbine, the combination of 100 a pressure-chamber, bucket-rings on opposite side-walls, a shaft, and a nozzle-carrying arm on said shaft mounted to turn on its longitudinal axis between said bucket-rings.
3. In a steam-turbine, the combination of 105 a pressure-chamber, bucket-rings on opposite side-walls, a shaft, and a hollow nozzle-carrying arm through which the steam is conducted mounted on said shaft to turn on its longitudinal axis between said bucket-rings.
4. In a steam-turbine, the combination of 110 a pressure-chamber, bucket-rings mounted on opposite side-walls, a shaft, an arm mounted radially on said shaft between said bucket-rings, a nozzle on said arm, and means inclosed by the shaft to turn said arm. 115
5. In a steam-turbine, the combination of 120 a pressure-chamber, bucket-rings mounted on opposite side-walls, a shaft, an arm mounted radially on said shaft between said bucket-rings, a nozzle on said arm, and a spindle inclosed by the shaft to turn said arm.
6. In a steam-turbine, the combination of 125 a pressure-chamber, bucket-rings mounted on opposite side-walls, a shaft, an arm mounted radially on said shaft between said bucket-rings, a nozzle on said arm, a spindle inclosed by the shaft to turn said arm, and a steam-cylinder and piston to operate said spindle.
7. In a steam-turbine, the combination of 130

- a pressure-chamber having oppositely arranged bucket systems, a shaft, an oscillating arm mounted on said shaft between said systems, a nozzle carried by said arm to impinge the steam against said buckets, and bucket-segments also carried by said arm.
8. In a steam-turbine, the combination of a pressure-chamber having oppositely arranged bucket-rings, a shaft, nozzle-carrying arms mounted on said shaft between said bucket-rings at an angle of 180° with respect to each other, and means to turn said arms about their longitudinal axes in order to bring their nozzles into coöperation with the bucket-rings at one or the other side thereof.
9. In a steam-turbine, the combination of a pressure-chamber having bucket-rings on opposite side-walls, a shaft passing through said chamber, and arms mounted on said shaft within said chamber and carrying nozzles movable into coöperation with the bucket-rings on either wall.
10. In a steam-turbine, the combination of a pressure-chamber having oppositely arranged bucket-rings on opposite side-walls, hollow arms mounted to rotate in said chamber about a common axis, means for conducting the steam to the interior of said arms, nozzles carried by the arms at their outer ends, bucket-segments carried by the arms to fit between the buckets of the bucket-rings and receive the steam from the nozzles, and means for turning said arms about their longitudinal axes whereby said nozzles and segments are brought into coöperation with one or the other set of bucket-rings.
11. In a steam-turbine, the combination, with the hollow arms and the nozzles carried thereby, of adjusting mechanism for the nozzles housed within said arms.
12. In a steam-turbine, the combination of a shaft, a hollow arm mounted thereon, a nozzle at the outer end of said arm, adjusting mechanism for the nozzle housed within the arm, and means in connection with said shaft to operate said adjusting mechanism.
13. In a steam-turbine, the combination of a shaft, a hollow arm mounted thereon, a nozzle at the outer end of said arm, adjusting mechanism for the nozzle housed within the arm, and means comprising a spindle in-
- closed by said shaft for operating said adjusting mechanism.
14. In a steam-turbine, the combination of a shaft, a hollow arm mounted radially thereon, a nozzle at the outer end of said arm, a rod within said arm to adjust said nozzle, a spindle inclosed by the shaft, an operative connection between said spindle and said rod, and actuating mechanism for said spindle.
15. In a steam-turbine, the combination of a pressure-chamber, bucket-rings mounted on both side-walls thereof, a shaft in said chamber, arms on said shaft through which the steam is conducted, bucket-segments on said arms, and means for turning said arms to move said segments into coöperation with the bucket-rings on either side-wall.
16. In a steam-turbine, the combination, with the reversing mechanism comprising a cylinder 12 and a piston 11 within the same, of a cylinder 28 and piston 26 to control the admission of steam to the turbine, and the automatic connection between said cylinders whereby the steam is shut off during the reversal of the turbine.
17. In a steam-turbine, the combination, with the reversing mechanism embodying a spindle shiftable longitudinally within the shaft, a cylinder 12, and a piston 11 within said cylinder operatively connected with said spindle, of means to control the admission of steam to the turbine, and an automatic connection between said cylinder 12 and said controlling means whereby during the reversal of the turbine the admission of steam is discontinued.
18. In a steam-turbine, the combination, with the pressure-chambers and the shaft passing through the same and having grooved portions between the pressure-chambers, of labyrinth packings in said grooves, pivoted levers fixed to said packings, and bolts for adjusting said levers.
- In testimony, that I claim the foregoing as my invention, I have signed my name in presence of two subscribing witnesses.
- JAN PROCNER.
